(57) **CLAIM**

The ornamental design for a coffee grounds homogenizer, as shown and described.

DESCRIPTION

FIG. 1 is a top perspective view of a coffee grounds homogenizer;

FIG. 2 is another top perspective thereof showing the cap detached from the body;

FIG. 3 is a front view thereof;

FIG. 4 is a left side view thereof, with the right side being a mirror image;

FIG. 5 is a rear view thereof;

FIG. 6 is a top view thereof;

FIG. 7 is a bottom view thereof;

FIG. 8 is a front view thereof without the cap;

FIG. 9 is a left side view thereof without the cap, with the right side being a mirror image;

FIG. 10 is a rear view thereof without the cap;

FIG. 11 is a top view thereof without the cap;

FIG. 12 is a bottom view thereof without the cap;

FIG. 13 is a side view of the cap;

FIG. 14 is the top view thereof; and,

FIG. 15 is another top perspective view thereof without the cap showing the homogenizing wires in an extended position.

The broken lines in the drawing depict portions of the coffee grounds homogenizer that form no part of the claimed design.
